UNITED STATES PATENT OFFICE.

RUDOLPH SCHNEIDER, JR., OF MONROE, WISCONSIN.

SLIDING-DOOR HANGER.

1,099,399.

Specification of Letters Patent.

Patented June 9, 1914.

Application filed November 6, 1913. Serial No. 799,548.

To all whom it may concern:

Be it known that I, RUDOLPH SCHNEIDER, Jr., citizen of the United States, residing at Monroe, in the county of Green and State 5 of Wisconsin, have invented certain new and useful Improvements in Sliding-Door Hangers; and I do declare the following to be a full, clear, and exact description of the invention, such as will enable others skilled in 10 the art to which it appertains to make and use the same.

This invention relates to door hangers, and more especially to the roller carriages employed therein, and the object of the same 15 is to produce a hanger whose rollers are adjustably or reversibly mounted in its carriages so that the latter may be applied with either side plate out. To this end the carriage is in two plates or parts connected by 20 the horizontal and vertical pins which form the bearings for the said rollers and held in connected position by the bolts which attach the parts to the door.

Other details of the carriage are herein- 25 after more fully described and claimed, and are shown in the drawings wherein—

Figure 1 is a side elevation of a portion of a freight car with this improved door and hanger applied; Fig. 2 is an enlarged view 30 of the hanger alone, as seen from the inside; Figs. 3 and 4 are sections through the hanger part of the framework of the car, and the door, taken on the lines 3—3 and 4—4 respectively of Fig. 2. Fig. 5 is a 35 horizontal section of the hanger on the line 5—5 of Fig. 2, the dotted lines indicating how the rollers might be mounted. Fig. 6 is a detail elevation of the outside plate of the hanger, viewed from its inside; and 40 Fig. 7 is a similar detail of the inside plate of the hanger viewed also from its inside.

My invention is shown as applied to a 45 rolling door on the side of a freight car, although it is obvious that it is not limited to this application.

In the drawings the letter F designates the floor of a car overlying a side beam or sill S, and W is the wall of the car alongside of which moves the door D as usual. Be- 50neath the door opening and to one side of the same a track T is mounted on brackets consisting of castings C disposed about eighteen inches apart and held to the sill S by bolts B passing through the track and cast- 55 ings and by lag screws L passing through the castings only; and this construction is

duplicated in inverted form along the top of the door opening and to one side of the door. For a six-foot opening the tracks will be twelve feet long and the castings C along 60 the top track need not be so close together, or in fact some other form of guide might be used at the top of the door without departing from the spirit of my invention. I will therefore refer hereinafter to the lower 65 edge of the door only. On the lower track T travels a horizontal roller H having a flange f which moves inside the rail, and inside the casting at each corner of the door is mounted a vertical roller V whose face 70 travels against the wall W opposite the sill S. Both rollers are extended as at E at their ends into what might be called hubs to reduce friction. I speak of the rollers as horizontal and vertical on account of the position of their axes. 75

Coming now to the details of the present invention, the carriage in which these rollers are supported is duplicated at the lower corners of the door, and as above suggested 80 there may be two other carriages at the upper corners of the door if there is an overhead track of similar construction, and I will describe but one carriage. One member of this carriage I will call the outer plate 1, 85 its body being pierced with a plurality of bolt holes 2 and its lower edge provided with an inwardly projecting lip 3 for a purpose yet to appear. Some distance above 90 said lip the body is provided on its inner face with a horizontal flange 4 having two upright holes 5 and 5'. The lip and the flange are at one edge of this member and at its lower end, and at the other edge the plate is thickened as at 8 and provided with 95 a socket 9 in its inner face at the center of the thickened portion. Between the lip and the flange the plate is provided with a rectangular opening 7. The other member con- 100 stitutes what might be called the inner plate 11 whose upper portion is provided with bolt holes 12 registered with those numbered 2 in the outer plate 1, whose lower portion is provided on its outer face with a horizontal lip 13 adapted to overlie the flange 4 105 and pierced with holes 15 and 15' register- 110 ing with the holes 5 and 5', whose lower edge is provided with a flange 14 adapted at its inner edge to overlie the lip 3 on the outer plate 1 and formed with sockets 16 and 16' in its upper face directly beneath the holes 5 and 5', and whose body between the

lip 13 and the flange 14 is provided with a rectangular opening 17 for a purpose yet to appear. The parts thus described are located at one edge of this member, and at the 5 other edge of its lower end its body is thickened as at 18 and provided with a socket 19 in its outer face at the center of the thickened portion.

The bearing for the horizontal roller H is 10 a half-inch steel pin 10 whose extremities are shaped to fit the sockets 9 and 19, and the bearing for the vertical roller V is a quarter-inch steel pin 20 whose lower extremity fits into a socket 16 and whose upper 15 portion passes through the alined holes 5 and 15. It is obvious that this pin need not be so large as that which passes through the horizontal roller H because the latter supports the weight of the door. Ordinary bolts 20 21 pass through the alined openings 2 and 12 and through the intervening door D, and hold the two members thereon, the nuts of these bolts being by preference on the outside of the door. In the drawings the position 25 of parts is that which they will assume when applied to the lower right hand corner of the door, but for the lower left corner the plates 1 and 11 will obviously be reversed and the pin 20 mounted in the holes 5' and 30 15' so that the vertical rollers shall yet project from the inside of the door and travel against the wall W.

In assembling the parts the pin 10 is put through the horizontal roller H and this 35 roller and the other are placed in position between the two members, which latter are brought together so that the flange of one engages the lip of the other as shown. This action will enter the extremities of the pin 40 10 in the sockets 9 and 19. The pin 20 is then dropped down through a hole in the lip 13, through the corresponding hole in the flange 4, through the bore of the vertical roller V, and its lower end into one of the 45 sockets 16 or 16'; and the presence of this pin holds the lower edges of the plates in proper position and prevents their spreading so that the extremities of the pin 10 could drop out of the sockets 9 and 19. It 50 will be observed that said extremities are not exposed on either side of the door, nor is the lower extremity of the upright pin 20 exposed. The entire carriage is then passed astride the body of the door D, and the bolts 55 21 passed through the alined holes 2 and 12 and through the door itself, and their nuts tightened up. The tread and flange of the horizontal roller H will now be below the lower face of the flange 14 on the member 60 11, ready to travel on the upper edge of the rail T, and the inner side of the roller V will project through the opening 17 and beyond the line of the thickened portion 8 of the member 11, ready to travel against the wall 65 W of the car. The other lower corner of the

door is then supplied with a similar carriage, excepting that its parts should be reversed as above suggested. The upper corners may then be supplied with similar carriages, or with any suitable guide to engage the upper 70 track, and finally the door is placed in position. All parts of this device are by preference of malleable casting, and in so far as possible I would make the bolts and the lag screws of standard size so that they may be 75 bought in the open market.

A striking feature of the invention is the absence of projections beyond the plates or members, and the simplicity of the structure without the sacrifice of advantages. 80 So long as the fastening bolts 21 hold the carriage on the door, the latter prevents the rise of the pin 20 and the loss of the roller V, and the bolts 21 prevent the spreading of the members and the dislodgment of the 85 pin 10 and loss of the roller H. The vertical roller holds the device away from the car-side, and the flanged horizontal roller sustains the weight of the door and prevents derailment from the track T if any suitable 90 overhead hanger is employed.

What is claimed as new is:

1. A roller carriage for door hangers comprising a pair of members having alined holes in their upper portions, the lower portion of one member having a flange projecting toward the other and provided with a socket in its upper face and the wall of this member having an opening above said flange, the other member having a flange 100 projecting toward the first-named member and provided with a hole above said socket, a pin adapted to drop through said hole and rest at its lower extremity in said socket, and a roller mounted on said pin with its 105 body projecting through said opening.

2. A roller carriage for door hangers comprising a pair of members having alined holes in their upper portions, the lower portion of one member having a flange projecting toward the other and provided with a socket in its upper face and the wall of this member having an opening above said flange, and this member having a lip above 110 said flange projecting toward the other member and provided with an upright hole above said socket, the other member having a flange projecting toward the first-named member below said lip and provided with a hole adapted to aline with that in the lip, 115 a pin through said alining holes with its lower extremity resting in the socket, and a roller mounted on said pin with its body 120 projecting through said opening.

3. A roller carriage for door hangers 125 comprising a pair of members, the lower portion of one member having a flange projecting toward the other and provided with a socket in its upper face and the wall of this member having an opening above said 130

- flange, and this member having a lip above said flange projecting toward the other member and provided with an upright hole above said socket; the other member having 5 a lip at its lower edge adapted to underlie said flange, and above said lip a flange projecting toward the first-named member and adapted to underlie its lip and pierced with a hole registering with the hole in such lip, 10 a pin through said alining holes with its lower extremity resting in the socket, and a roller mounted on said pin with its body projecting through said opening.
4. In a roller carriage for door hangers, 15 the combination with a pair of plates having inter-engaging lips and flanges at their lower portions near one edge and their bodies having openings between said flanges, both plates being thickened at their lower 20 portions near their other edges and provided with sockets in the inner faces of the thickened portions; of a horizontal pin removably mounted in said sockets, a roller mounted on this pin, a vertical pin connecting said flanges, and a roller journaled on this pin and projecting through one of said 25 openings.
5. In a roller carriage for door hangers, the combination with a pair of plates adapted to be secured to opposite faces of a door, 30 one plate having at its lower end at one edge a flange projecting toward the other and provided with a socket in its upper face, and the other plate having above such flange 35 a second flange projecting toward the first-named plate and pierced with an opening
- above said socket, both plates having sockets on their inner faces adjacent their other edges; of a horizontal pin mounted in the last-named sockets, a roller journaled thereon, an upright pin mounted in the hole in one flange and the socket in the other, and a roller journaled on this pin.
6. A roller carriage for door hangers comprising a pair of members, the lower 45 portion of one member having a flange projecting toward the other and provided with two sockets in its upper face and the wall of this member having an opening above said flange, and this member having a lip above 50 said opening projecting toward the other member and provided with upright holes above said sockets; the other member having a lip at its lower edge adapted to underlie said flange, and above said lip a flange 55 projecting toward the first-named member and adapted to underlie its lip and pierced with holes registering with those in such lip, and this member having an opening in its wall between the flange and the lip; a 60 pin through a pair of said alining holes with its lower extremity in one socket, and a roller mounted on said pin with its body projecting through one of said openings.
- In testimony whereof I have hereunto set 65 my hand in presence of two subscribing witnesses.
